UNITED STATES PATENT OFFICE.

J. WARREN BUTTON, OF SCHAGHTICOKE, NEW YORK.

BUTTER-WORKER.

SPECIFICATION forming part of Letters Patent No. 390,565, dated October 2, 1888.

Application filed November 7, 1887. Serial No. 254,526. (No model.)

To all whom it may concern:

Be it known that I, J. WARREN BUTTON, a citizen of the United States, residing at Schaghticoke, in the county of Rensselaer and State of New York, have invented certain new and useful Improvements in Butter-Workers; and I do hereby declare the following to be a full, clear, and exact description of the invention, such as will enable others skilled in the art to 10 which it appertains to make and use the same.

This invention relates to an improvement in butter-workers, the object thereof being to provide a simple, cheap, and efficient device for compressing the butter after it has been removed from the churn, so as to remove therefrom all surplus water and other waste material; and it consists in the construction, arrangement, and combination of parts, substantially as will be hereinafter described, and then 15 particularly pointed out in the claims.

In the accompanying drawings, Figure 1 is a perspective view of my improved butter-worker. Fig. 2 is a side elevation of the same, showing the compressor or follower in the position which it occupies when at one end of its stroke. Fig. 3 is a similar side elevation showing the compressor or follower in the position that it occupies when at the other end of the stroke. Fig. 4 is a bottom plan view. Fig. 25 5 is a top plan view of the tray with the follower and actuating mechanism removed.

Like letters of reference denote like parts in all the figures.

A represents a tray made of suitable shape and size, and consisting simply of a bottom portion and three sides arranged about the same, the remaining side and the top being left open. This tray is mounted removably upon a supporting frame-work consisting of three 35 40 legs, *a a*, secured to a horizontal triangular frame, *b*.

Blocks or projections *c* on the bottom of the tray are properly located to enter the corners of the triangular frame when the tray has been 45 located thereupon, and thus keep the tray in proper position during the operation of the butter-working mechanism. It will thus be seen that the tray can be easily removed from the supporting-frame and carried about from 50 one room to the other during the process of

butter-making. The tray is, therefore, as convenient for use as the ordinary butter-bowl.

The butter-working mechanism consists of an operating hand-lever, *B*, which is pivoted at its lower end to the tray at a point adjacent to the open end of the same. Within the tray is loosely located a flat block or follower, *C*, having a width substantially equal to the depth of the tray and a length substantially equal to the width of the tray. To this block 55 60 is rigidly secured a rod or bar, *D*, which is pivoted at its outer end to the hand-lever *B* at a suitable point on said lever above the bottom of the tray. The rod *D* is preferably provided with a series of several holes, so that 65 the point of its pivotal connection with the lever *B* may be varied, in order to adjust and regulate the working of the block or follower *C*.

The block or follower *C* and the rod *D* are 70 placed approximately at right angles to each other, said follower being secured to the rod in a slightly-inclined position, as shown, and a brace, *d*, may be fixed between them, if wished.

The operation of my improved butter-worker may be briefly described as follows: The butter to be worked is placed in the tray between its closed end and the block or follower *C*. The operator then lays hold of the 75 80 hand-lever *B* and moves it to and fro, which causes the follower *C* to reciprocate. When the lever *B* is moved inward in the direction of the mass of butter, follower *C* will be pressed against the butter, which will be confined in 85 the narrow space between the tray and follower. The position taken by the several parts when the lever is at the inner limit of its stroke is clearly shown in Fig. 3. It will here be seen that the follower *C* is inclined at 90 a considerable angle to the side of the tray *A*, and that consequently the butter which is confined between said follower and tray will have a wedge shape, being much heavier at the top than at the bottom. Therefore, when the operator moves the hand-lever *B* in the opposite direction, and consequently removes the follower *C* from contact with the butter, the latter, being heavier at the top, will fall down toward the follower, so that when the operator 95 100

next forces the follower against the butter it will press upon it in a different manner from what it did before. When the follower is in that position which in the ordinary operation of the machine may be termed the "outer limit" of its stroke, it will be noted, by referring to Fig. 2, that said follower is substantially parallel to the end of the tray and is not in the inclined position which it assumes at the inner limit of its stroke. This change of position is due to the combination and arrangement of the several parts of my machine as I have described them, the arm D being rigidly secured to the follower and pivoted to the operating-lever at a point above the bottom of the tray, and it is by virtue of this peculiarity of construction, which permits the follower to operate as stated, changing its position from that shown in Fig. 2 to that shown in Fig. 3, and vice versa, that I am enabled to produce the improved results in the working of butter. If the follower maintained its inclined position constantly during its entire movement, the butter would have a tendency to slide up the inclined face of the follower when the latter begins to press against it; but since the follower, when it begins to press upon the butter, has the position shown in Fig. 2, the butter will be firmly compressed between said follower and the end of the tray, and all tendency to slide up the face of the follower will be overcome. At each compression of the mass of butter it is obliged, owing to the peculiar arrangement and construction of parts of my improved butter-worker, to be turned, so that the force of compression is exerted upon different parts of the mass. In this manner a thorough removal of the brine and buttermilk from the butter is effected. The waste substances that are expressed from the butter will run down into the bottom of the tray and toward the open end thereof. Said tray may be slightly inclined, if desired, to permit the water and brine to run off freely, and at the outer end I have found it convenient to make grooves therein, which center at an aperture made through the bottom of the tray.

In the corner of the tray opposite to the follower I have found it convenient to place a block or strap, as *k*, to enable the butter in said corner to change its position at each compression. The follower, when it reaches its inner limit, will ride up on this strip or piece *k*, thus becoming elevated in such a manner as to be further inclined, and also acting better upon the butter in the corner of the tray. Without this block the apex of the compressed wedge of butter will have a tendency to be drawn outward when the follower begins its return reciprocation—a movement on the part of the butter which would prevent its being automatically turned, as above described. The provision of the strip *k*, however, overcomes this tendency, for the strip holds the point of

the butter and allows the automatic turning of the wedge to take place when the follower recedes therefrom. Furthermore, the strip is beneficial in permitting the butter at the apex of the wedge to be changed in position, since without this strip it is obvious that the same butter will be likely to remain in the corner of the tray at all times. Furthermore, the movable follower may have the face which comes in contact with the butter fluted vertically, if desired; or it may be fluted in any other suitable manner. However, it will be noted that I do not confine myself to this fluting, but reserve the liberty to adopt it or not, as may be preferred. I have herein mentioned that the butter-worker was to be operated by power applied to a hand-lever. This power will ordinarily be the hand of the person using the machine; but it is obvious that if the user so desires other means of power may be applied.

The device herein described, although preferred for use as a butter-worker, may be employed for other purposes. It may, for instance, be used for kneading bread, and doubtless other places can be found where it can be employed with efficacy and value.

I am aware that butter-workers have heretofore been constructed having an oblong bowl containing a ladle-shaped follower attached to a rod to which an operating-lever is pivotally connected, whereby the ladle is reciprocated and the butter compressed. Such construction I do not therefore claim, broadly, as new with me.

Having thus described my invention, what I claim as new, and desire to secure by Letters Patent, is—

1. In a butter-worker, the combination, with the tray, of an operating-lever pivoted to the bottom of the tray and a connecting-rod pivoted to the operating-lever at a suitable distance above the tray-bottom and provided at its forward end with a follower extending the width of the tray fixedly attached thereto, substantially as described.

2. In a butter-worker, the combination of the tray, a follower or compressor arranged to reciprocate therein, a block or strip secured horizontally in the corner of said tray opposite the follower, and upon which the follower rests when at the inner limit of its stroke, an operating-lever pivoted to the tray-bottom, and a connecting-rod rigidly fastened to the follower and pivoted to the operating-lever above its pivotal point, substantially as described.

In testimony whereof I affix my signature in presence of two witnesses.

J. WARREN BUTTON.
